DESIGN FOR A DOLL

Henry Levy, Merrick, N. Y.

Application May 15, 1940, Serial No. 92,378

Term of patent 3½ years

To all whom it may concern:

Be it known that I, Henry Levy, a citizen of the United States, residing in Merrick, county of Nassau, and State of New York, have invented a new, original, and ornamental Design for a Doll, of which the following is a specification, reference being had to the accompanying drawing, forming part thereof.

I claim:

The ornamental design for a doll, as shown.

HENRY LEVY.
